CONTROL APPARATUS

Lars O. Grondahl, Pittsburgh, and Paul N. Bossart, Cheswick, Pa., assignors to The Union Switch & Signal Company, Swissvale, Pa., a corporation of Pennsylvania

Application October 8, 1941, Serial No. 414,100

7 Claims. (Cl. 246—124)

Our invention relates to control apparatus, and it has particular reference to the organization of such apparatus into control systems for railroads arranged to provide at a given point a warning or indication that a train is approaching such point.

It has been proposed heretofore to provide apparatus for approach controlling or indicating, in cases where the control or indication required is an essential element of a permanent signaling system, by means permanently installed as a portion of the signal system and usually involving track circuits together with the necessary insulated rail joints. At times, however, it is desirable temporarily to approach control or indicate the approach of a train at a given point, as for example during the time that a construction or maintenance crew is working on a given section of track, or for the period that relatively heavy highway traffic is caused to travel an unprotected crossing, ordinarily handling a small amount of traffic, due to a detour on a main highway. In these latter cases, the expense of installing insulated joints, and in the accompanying interference with traffic moving over the track during the insulation of the joints, may not warrant the use of the usual track circuit apparatus for controlling the approach warning or indication devices.

It is an object of our present invention to provide systems involving readily portable and easily installed apparatus arranged to provide an approach control or indication when a train approaches a given point on a trackway.

Another object is to provide means arranged to be independent of the usual track circuit apparatus and functioning to provide a warning or indication when a train approaches a given point on a trackway.

An additional object is to provide an approach control system involving readily portable, easily assembled apparatus arranged to avoid the necessity of using line wires or cables extending along the trackway.

A further object is to provide novel and improved approach control and indication systems.

The above-mentioned and other important objects and characteristic features which will become readily apparent from the following description of our invention, are attained in accordance with the invention by utilizing a track instrument, operatively associated with a rail of a stretch of track, for connecting a source of current through the contact of the instrument to a relay at a point remote from the

source in a non-train-shutable track circuit including at least one rail of the stretch and a conductor. The conductor may comprise an earth or ground connection, or may, as in the case of a stretch of multiple track road, comprise a track rail of another track of such road.

We shall describe several forms of apparatus embodying our invention, and shall then point out the novel features thereof in claims.

10 In the accompanying drawing, Fig. 1 is a diagrammatic view showing one form of apparatus embodying our invention. Fig. 1a is a sectional view of a track instrument forming part of the apparatus illustrated in Fig. 1. Figs. 2, 3 and 4 are diagrammatic views illustrating modified forms of the apparatus represented in the drawing, and each embodying our invention. In each of the several views, similar reference characters have been employed to designate corresponding parts.

Referring to Fig. 1, the reference character X designates a stretch of railway track over which traffic normally moves in the direction indicated by an associated arrow, or from left to right as viewed in the drawing. Operatively associated with a rail of the stretch is a track instrument, designated by the reference character M, having a contact which is operated by a vertical movement of the rail or a blow of the wheel. Instrument M may be of any suitable form and for the purposes of the present description we shall assume that instrument M is of the microphone type described and claimed in Letters Patent of the United States No. 1,834,077, granted December 1, 1931, to A. J. Sorensen. Referring particularly to Fig. 1a, a track instrument M of the microphone type is represented attached to a rail by means of a clamp 4 which is secured to the base of the

30 rail by a lug 3 and a bolt 5. The microphone comprises an insulating housing 6 attached to clamp 4 by a screw 7, and which housing contains two spaced vertically disposed metal electrodes 8 and 9. The space between these electrodes is at least partially filled with carbon granules 10, and the parts are so proportioned that under the conditions when microphone M is not vibrated, the resistance between the electrodes 8 and 9 through the carbon granules is

35 relatively low, but when the microphone is vibrated and the carbon granules are agitated, the resistance between the two electrodes is greatly increased.

40 Instrument M has its contact, comprising the electrodes and carbon granules, interposed in the

45 50 55

circuit connection of a source of current, such as battery 2, across a conductor and but one track rail of stretch X, and a relay R is connected across the one rail and the conductor at a point remote from the source. When instrument M is not vibrated, sufficient current flows through the instrument, the one track rail, relay R and the conductor to energize the relay, but when instrument M is actuated by a train and its carbon granules are agitated, the resistance between electrodes 8 and 9 increases to cause in turn the current flowing through the track rail and conductor to decrease to a value below that required to hold up relay R. Relay R at this time is caused to release and close its back contact 11 to complete an obvious energizing circuit, including a source of current 12, for a device K. The device K may, for example, comprise a highway crossing signal, or as shown may comprise an indicator for warning track crews or gangs of the approach of a train. It follows that when a train on track X actuates track instrument M, relay R is caused to release and indicator K is energized to indicate that a train is approaching. After the train passes the track instrument, relay R of course becomes energized to deenergize indicator K and restore the apparatus to its normal condition.

The conductor forming a portion of the circuit of relay R may, as indicated in Fig. 1, be a ground or earth path having a ground terminal G1, or as represented in Fig. 2, the conductor may be a rail of a second track X1 of a multiple track railroad. In either case, the circuit of relay R employs a single rail of any one track and is arranged to avoid the necessity of line wires or cables extending along the trackway.

Referring now to Fig. 2, a second track instrument M1 is represented operatively associated with a rail of a second track X1, and both instruments M and M1 of Fig. 2 cooperate in controlling an obvious circuit for a traffic responsive relay MR. If desired, however, relay MR may be arranged to be responsive to traffic on either one but not both of the two tracks, in which event only the one track instrument associated with the selected one track would be employed. Relay MR is energized when the track instruments are unactuated, and relay MR closes its front contact 15 to connect a suitable source of alternating current, such as a generator not shown in the drawing but having its opposite terminals designated by the reference characters BX and CX, to primary winding 16 of a transformer 17. Secondary winding 18 of transformer 17 has one terminal connected to a selected one of the track rails of stretch X and has its other terminal connected to a selected one track rail of stretch X1.

Relay R is connected across the selected one track rails of the two tracks, over a stick circuit including its own front contact 20. Relay R may be of the alternating current type directly responsive to the alternating current impressed by transformer 17 across the selected rails of the two tracks, or as shown relay R may be of the direct current type, in which event a rectifier 21 is interposed in the connection of the relay to the track rails for rectifying the alternating current into and supplying relay R with rectified current. Relay R controls an associated indicator K over its back contact 11, and is arranged so that when once released due to a train actuating either one of the track instruments M and M1, relay R opens its front contact 20 to interrupt its circuit at that point. An acknowledging switch AS is provided

and may be closed to provide an alternate path around front contact 20 in the circuit of relay R, and it follows that when relay R is released, it remains released until track instruments M and M1 become inactive and acknowledging switch AS is closed. When these conditions exist, relay R picks up and closes its front contact 20 to complete its previously mentioned stick circuit, whereupon acknowledging switch AS may be opened and the apparatus is restored to its normal condition as represented in the drawing.

The rails of stretches X and X1 may, as shown in Fig. 2, be divided by insulated joint j at a point intermediate the connection of the source and relay to the track rails. The current from source BX-CX may be transmitted around these joints to relay R by any suitable means, as by a transformer 23 having its primary winding 24 connected across the selected rails of tracks X and X1 on one side of the joints and having a secondary winding 25 connected across the selected track rails on the opposite side of the joints.

The apparatus embodying our invention may also be employed on a track over which traffic travels in either direction, and be arranged so as to provide a warning or indication when a train approaches a point on the trackway but not when it recedes from such point. Such an arrangement is represented in Fig. 3, and it employs interlocking relays, designated by the reference character XR with suitably distinguishing suffixes. These relays may be of any suitable type such as, for example, the type disclosed in Letters Patent of the United States No. 1,799,629, granted on April 7, 1931, to W. K. Lockhart and T. J. O'Meara. These relays are well-known and comprise two windings W1 and W2 and an interlocking mechanism which cooperates with the armature of the windings in such manner that when winding W1 is the first of the two windings to be deenergized, its armature releases and its front contact 27 becomes opened, but when winding W2 is the first winding to be deenergized, the interlocking mechanism is caused to latch up the armature of winding W1 and prevent front contact 27 from opening when winding W1 is subsequently deenergized during the interval that winding W2 is still deenergized. When front contact 27 of winding W1 is closed, a suitable source of alternating current, such as a generator, designated by the reference character f1, and generating current having a preselected frequency, has one terminal connected to one rail of track X and has its other terminal connected to one rail of track X1.

Referring to Fig. 3, interlocking relay XR1 is represented as being employed for providing an approach control or indication when trains operate on tracks X and X1 in the eastbound direction, or from left to right as viewed in the drawing. Winding W1 of relay XR1 is energized over an obvious circuit governed by instruments M and M1, while winding W2 of relay XR1 is energized over another obvious circuit governed by instruments M2 and M3, which instruments are operatively associated one with each track of the represented double track road. Instrument M2 is located along the trackway at a point such that it will be actuated by an eastbound train after such train has actuated instrument M associated with the same track X, while instrument M3 is likewise located along track X1 at a point where it will be actuated subsequent to an eastbound train on track X1 actuating the other instrument M1.

At the selected point on the trackway where it is desired to provide an indication, a relay R_1 is connected across the selected rails of tracks X and X_1 through a tuning unit TU_1 and a transformer 28 . Transformer 28 has its primary winding 29 connected across the selected one rail of track X and the selected one rail of track X_1 , and has its secondary winding 30 connected to relay R_1 through tuning unit TU_1 . The details of construction of unit TU_1 are not shown in the drawing, but such unit comprises a resonant rectifier unit and usually includes a reactor condenser tuning unit tuned to resonance at a frequency corresponding to the frequency of current supplied from the source f_1 , and a rectifier for rectifying such current into and supplying relay R_1 with unidirectional current. It is apparent, therefore, that when front contact 27 of winding W_1 of relay XR_1 is closed, relay R_1 is energized by current of the selected frequency supplied from the source f_1 . When relay R_1 is released, its back contact 11 completes an obvious energizing circuit for an associated indicator K .

Another interlocking relay XR_2 is employed for enabling an indication to be provided when traffic operating in the other or westbound direction on the tracks X and X_1 approaches the selected point. Windings W_1 and W_2 of relay XR_2 are controlled in a manner corresponding to that pointed out in detail for relay XR_1 , and when front contact 27 of winding W_1 of relay XR_2 is closed, it connects a source of current, distinctively different from the source f_1 , across one rail of track X and one rail of track X_1 . The source of current associated with relay XR_2 may be unidirectional in character, or as shown may comprise a generator f_2 , generating current having a frequency distinctively different from the frequency of current generated by source f_1 . To detect this distinctively different current, a relay R_2 is provided at the selected point and is connected through a second tuning unit TU_2 to secondary winding 30 of relay R_2 . The unit TU_2 is a resonant rectifier unit tuned to resonance at a frequency corresponding to the frequency of current supplied from the source f_2 . If, however, the source f_2 is a source of unidirectional current, then unit TU_2 would be dispensed with, and relay R_2 would be connected to the one rail of track X and to the one rail of track X_1 through a direct connection which may include a reactor for blocking the flow of alternating current supplied from the source f_1 . Relay R_2 when released completes at its back contact 32 an obvious energizing circuit for a device, which may be indicator K associated with relay R_1 , or as shown may be a second indicator K_1 . As will be made clear presently, the advantages of using two indicators, K and K_1 , one for each relay R_1 and R_2 is that the two indicators permit the direction of the approaching train to be indicated, whereas a single indicator would only signify that a train is approaching and would not indicate the direction of movement of such train.

When an eastbound train operates on either track X or X_1 , winding W_1 of relay XR_1 is caused to release when the train actuates instrument M or M_1 , as the case may be. Winding W_2 also is released when such train actuates the other track instrument M_2 or M_3 , but since winding W_1 was first released, its front contact 27 opens to disconnect the source f_1 from the one rail of tracks X and X_1 . Relay R_1 accordingly releases and indicator K becomes energized.

to indicate or warn that an eastbound train is approaching.

After the train passes the location of instruments M and M_1 associated with relay XR_1 , winding W_1 of relay XR_1 picks up and closes its front contact 27 to reconnect the source f_1 across the rails of tracks X and X_1 , and relay R_1 accordingly becomes energized and opens its back contact 11 to deenergize indication device K .

10 Then, when the train passes the location of the other instruments, M_2 and M_3 , associated with relay XR_1 , the other winding W_2 becomes energized and relay XR_1 accordingly is restored to its normal condition.

15 When the train reaches the location of the track instruments associated with relay XR_2 , instrument M_2 or M_3 , as the case may be, becomes actuated and winding W_2 accordingly is released to cause the interlocking mechanism of relay XR_2 to prevent the opening of front contact 27 of winding W_1 of relay XR_2 when that winding subsequently becomes released due to the actuation of instrument M or M_1 . The source f_2 associated with relay XR_2 accordingly is not disconnected from the track rails at this time, hence relay R_2 remains energized and it follows that an eastbound train does not cause a second indication to be exhibited when such train recedes from the selected point. Windings W_2 and W_1 are, of course, caused to become energized in the order named when the train clears the instruments associated with relay XR_2 , and the apparatus accordingly is restored to its normal condition as represented in the drawing.

20 When a westbound train operates over either track X or X_1 , indicator K_1 is caused to become energized by the apparatus of Fig. 3 in a manner believed to be obvious from an inspection of the drawing, and further detailed explanation is believed to be unnecessary.

25 There is a remote possibility that the apparatus represented in Fig. 3 might not function to provide an indication of an approaching train when trains operating in opposite directions on tracks X and X_1 pass the track instruments associated with one of the relays XR , for example, should a receding eastbound train on track X_1 start to pass instruments M_3 and M_1 associated with relay XR_2 , just prior to a westbound train on track X reaching the location of the other associated instruments M and M_2 , then winding W_2 would be first released and would latch up winding W_1 to prevent the opening of its front contact 27 . This obviously prevents release of relay R_2 and hence would not afford an indication that the westbound train is approaching. If it is desired to guard against this contingency, another interlocking relay may be associated with relay XR_2 , and such interlocking relays may be arranged to be controlled by traffic on only one but not both of the tracks. Thus, for example, relay XR_2 might have its winding W_1 controlled by instrument M and its winding W_2 controlled by instrument M_2 , while the other relay would have one of its windings controlled by instrument M_1 and its other winding controlled by instrument M_3 . The circuit connection of source f_2 to the one rail of each track X and X_1 would then be carried over front contact 27 of relay XR_2 connected in series with a front contact of the one winding of the other interlocking relay controlled by instrument M_1 . This arrangement would insure that a proper indication is provided at all times when a westbound train on

either track approaches the location of relay R2. In like fashion, a second interlocking relay may be associated with relay MR1 and the two interlocking relays may be arranged in the manner described to provide an indication whenever an eastbound train on either track approaches the location of relay R1.

In Fig. 4, relay MR is controlled by an associated pair of instruments M and M1, and a second relay MR1 is controlled by another pair of instruments M and M1. Relay MR, when picked up, completes at its front contact 35 an energizing circuit for an oscillator 36, which oscillator has one of its output terminals connected to a center terminal of a resistor 37 connected to the two rails of track X in multiple, and has its other output terminal connected to a center terminal of another resistor 38 connected across the two rails in multiple of the other track X1. Similarly, relay MR1 controls at its front contact 39 an obvious energizing circuit for an oscillator 40, which oscillator has its output terminals connected, one to the two rails in multiple of track X and the other to the two rails in multiple of track X1. The frequency of current supplied from oscillator 40 is distinctively different from the frequency of current supplied from oscillator 36.

An amplifier 42 is inductively coupled with the rails of tracks X and X1 by means of pick-up coils 43 disposed in inductive relation to the rails of tracks X and X1, and amplifier 42 supplies energy through tuning units TU1 and TU2 to relays R1 and R2, respectively. Unit TU1 is tuned to resonance at a frequency corresponding to the output frequency of oscillator 36, hence relay R1 is energized and picked up when front contact 35 of relay MR is closed. Unit TU2 is tuned to resonance at a frequency corresponding to the output frequency of oscillator 40, and relay R2 is energized and picked up when front contact 39 of relay MR1 is closed. The frequencies of current generated by oscillators 36 and 40 preferably are in the range of from 1000 to 10,000 cycles a second, and such high frequency currents are transmitted through the rails substantially independent of insulated joints in the rails. Circuits of the type illustrated are well-known and have been proposed heretofore for use in train communication systems.

When a train actuates either instrument M or M1 associated with relay MR, that relay is caused to release, oscillator 36 becomes deenergized, and relay R1 accordingly releases to complete an obvious circuit for indicator K. After the train passes the location of instruments M and M1 associated with relay MR, that relay picks up and oscillator 36 becomes active to cause relay R1 to pick up and deenergize indicator K. In like fashion, when the train passes instruments M and M1 associated with relay MR1, that relay is released, oscillator 40 is deenergized, and relay R2 accordingly is caused to release to energize indicator K1. After the train clears instruments M and M1 associated with relay MR1, that relay picks up and restores the apparatus to its normal condition, as represented in the drawing.

It is, of course, to be understood that the directional means provided for the apparatus of Fig. 3 may be incorporated into the apparatus of Fig. 4, whereupon indicator K may be energized only when an eastbound train actuates either instrument M and M1 associated with relay MR, and indicator K1 may be energized only when a westbound train actuates either instrument M

or M1 associated with relay MR1. In addition, it is to be noted that while the two rails of each track are employed in multiple in Fig. 4, the system may be arranged to employ only a single rail of each track, or if desired, but a single rail of one track and a ground return path.

Although we have herein shown and described only a few forms of control apparatus embodying our invention, it is understood that various changes and modifications may be made therein within the scope of the appended claims without departing from the spirit and scope of our invention.

Having thus described our invention, what we claim is:

- 15 1. In a warning system for railways, the combination with a stretch of double track railway, means responsive to traffic operating on either of said tracks, a warning device, a relay for operating said warning device, and means governed by said traffic responsive means for energizing said relay over a circuit including at least one track rail of each of the two tracks of said double track railway.
- 20 2. In combination, a stretch of double track railway, means responsive to traffic on either of said tracks, a source of current, a circuit controlled by said traffic responsive means for connecting said source across one rail of each of said two tracks, a relay connected across the said one rails of said two tracks over a circuit including its own front contact, warning means governed by said relay, and restoring means for at times providing an alternate path around said 35 front contact in its said circuit of said relay.
- 30 3. In combination, a stretch of double track railway, two track instruments one for each track of said railway, each track instrument operatively associated with a rail of its associated track, a source of current connected across one rail of each of said tracks over a circuit governed by each of said track instruments, a relay controlled by current derived from said one rail of said two tracks, said relay normally being energized over a circuit including its own front contact, a warning device controlled by said relay, and a manually operable switch for at times completing the circuit of said relay around its said front contact.
- 40 4. In combination with a stretch of double track railway, a relay connected across one rail of each of said tracks, a source of current connected across the same two rails at another point, and means interposed in said last mentioned connection and responsive to traffic on either of said tracks for controlling the connection of said source to said rails.
- 45 5. In combination with a stretch of railway track having two groups of two track instruments operatively associated therewith at spaced points, two relays at a point along said track intermediate the locations of said two groups of instruments, a first source of current connected to one of said two relays over a first circuit comprising one track rail and a conductor not comprising the other rail, a second source of distinctly different current connected to the other of said two relays over a second circuit comprising said one track rail and said conductor not comprising the other rail, means interposed in said first circuit and controlled by the instruments of one of said groups for interrupting said first circuit when said one group track instruments are actuated by a train operating on said track in 55 one direction but not the other, and means in-
- 60 6. In combination with a stretch of railway track having two groups of two track instruments operatively associated therewith at spaced points, two relays at a point along said track intermediate the locations of said two groups of instruments, a first source of current connected to one of said two relays over a first circuit comprising one track rail and a conductor not comprising the other rail, a second source of distinctly different current connected to the other of said two relays over a second circuit comprising said one track rail and said conductor not comprising the other rail, means interposed in said first circuit and controlled by the instruments of one of said groups for interrupting said first circuit when said one group track instruments are actuated by a train operating on said track in 65 one direction but not the other, and means in-
- 65 7. In combination with a stretch of railway track having two groups of two track instruments operatively associated therewith at spaced points, two relays at a point along said track intermediate the locations of said two groups of instruments, a first source of current connected to one of said two relays over a first circuit comprising one track rail and a conductor not comprising the other rail, a second source of distinctly different current connected to the other of said two relays over a second circuit comprising said one track rail and said conductor not comprising the other rail, means interposed in said first circuit and controlled by the instruments of one of said groups for interrupting said first circuit when said one group track instruments are actuated by a train operating on said track in 70 one direction but not the other, and means in-
- 75 8. In combination with a stretch of railway track having two groups of two track instruments operatively associated therewith at spaced points, two relays at a point along said track intermediate the locations of said two groups of instruments, a first source of current connected to one of said two relays over a first circuit comprising one track rail and a conductor not comprising the other rail, a second source of distinctly different current connected to the other of said two relays over a second circuit comprising said one track rail and said conductor not comprising the other rail, means interposed in said first circuit and controlled by the instruments of one of said groups for interrupting said first circuit when said one group track instruments are actuated by a train operating on said track in 75 one direction but not the other, and means in-

terposed in said second circuit and controlled by the instruments of the other of said groups for interrupting said second circuit when said other group track instruments are actuated by a train operating on said track in the other but not the one direction.

6. Directional warning means for indicating at a selected point along a stretch of railway track the approach of a train in either direction, said means comprising two sources of current of distinctively different character, relay means located at said selected point selectively responsive to currents of said different characters, a common circuit means including at least one of the rails of said stretch for supplying currents from said sources to said relay means from points disposed on opposite sides of said selected point when no train is approaching, means for interrupting the supply of one only of said currents to said relay means when a train approaches said selected point in one direction and for interrupting the supply of the other only of said currents when a train approaches said selected point in the other

direction, and warning means selectively controlled by said relay means.

7. Directional warning means for indicating at a selected point along a stretch of railway track the approach of a train in either direction, said means comprising a circuit including one only of the rails of said stretch, track instruments operatively associated with said stretch on opposite sides of said selected point, means separately controlled by each instrument for impressing on said circuit when no train is in the vicinity of the instrument a current which is distinctively different from that impressed on the circuit under the control of the other instrument and for interrupting such current when a train is in the vicinity of the associated instrument, and means receiving energy from said circuit at said selected point and selectively responsive to the different currents for controlling warning devices located at said selected point.
